DESIGN FOR A SHOE

Claude H. Daniels, Wellesley Hills, Mass.

Application June 24, 1933. Serial No. 48,518

Term of patent 14 years

To all whom it may concern:

Be it known that I, CLAUDE H. DANIELS, a citizen of the United States, and a resident of Wellesley Hills, in the county of Norfolk and State of Massachusetts, have invented, a new, original, and ornamental Design for a Shoe, of which the following is a specification, reference being had to the accompanying drawing, forming part thereof.

Referring to the drawing,

The figure is a side elevation of a shoe showing my new design.

The opposite side of the shoe presents substantially the same appearance as the side shown, one of the ornamental features of the design residing in the continuity of the vamp, substantially as shown, interrupted by an acute angle near the heel of the shoe.

I claim:

The ornamental design for a shoe, substantially as shown and described.

In witness whereof, I hereunto subscribe my name this 15th day of June, A. D. 1933.

CLAUDE H. DANIELS.
